CARL E. EKLIND AND KENNETH J. TOBIN, OF CHICAGO, ILLINOIS, ASSIGNEES TO
CAMEL COMPANY, OF CHICAGO, ILLINOIS, A CORPORATION OF ILLINOIS

CAR DOOR

Application filed December 17, 1927. Serial No. 240,910.

This invention relates to a metal car door and concerns itself primarily with a structure having a rigid and durable panel and a rigid and strong frame which are combined to produce a strong, durable structure that will shed the weather and excludes the same from entering between the frame and panel. In the past, metal car doors have not always been satisfactory, either the panel has been too weak, or else the frame surrounding the panel has been too weak, or the parts have not been rigidly connected. This invention seeks to overcome such objections by combining a stiff panel of requisite strength and durability with a strong and rigid frame that will withstand the severe strains and usage that the same must undergo and in which the frame is anchored to the panel against bending or distortion.

20 The invention comprises the novel structure and combination of parts hereinafter described and more particularly pointed out and defined in the appended claims.

In the accompanying drawings which illustrate a preferred embodiment of this invention and in which similar reference numerals refer to similar features in the different views:

Figure 1 is a side elevational view of a metal door involving this invention and shown as applied to the side of a house car.

Figure 2 is an enlarged and broken sectional view of the door taken in a transverse vertical plane thru the door.

35 Figure 3 is an enlarged fragmentary sectional view taken in a horizontal plane thru the front part of the door.

Figure 4 is an enlarged fragmentary sectional view taken in a horizontal plane thru the rear part of the door.

As shown on the drawings:

The present embodiment of this invention is illustrated as consisting of a sheet metal door comprising a frame consisting of an upper Z bar 1 which has one flange 2 extending upwardly behind a depending flange 3 of the supporting track which acts as a guide therefor. The other flange 4 of this Z bar extends downwardly and forms a sup-

port to which the sheet metal panel 5 of the door may be attached.

The frontal member of the frame consists of a Z bar 6 which has one flange 7 forwardly directed in a vertical plane and which is adapted for entering a vertical channel 8 formed by an angular weather proofing front edge angle 9 which is attached to the front door post 20. The other flange 10 of this Z bar is rearwardly directed and forms a support for the front edge of the sheet metal panel 5.

The bottom member of the frame consists of a Z bar 11 which has one flange 12 directed upwardly to form a support to which the lower margin of the panel 5 is attached. The other flange 13 of this Z bar is directed downwardly and extends behind suitable guide clips 14. The lower flange 13 may be provided with bulges or cam surfaces 14 that cooperate with the clips for forcing the door inwardly in its closed position.

The rear member of the frame consists of an angular member 15 having a flange 16 which is directed in a vertical plane to form a support to which the sheet metal panel is attached. This angular member has a flange 17 extending transversely of the door. This flange 17 forms the rear edge of the door and the same is provided with a forwardly bent portion 18 at a point beyond the inner side of the door. This bent portion cooperates with a curved flange 19 of a weather strip attached to the rear post of the door opening. In the present instance this rear post is shown in the form of a flange 20 on an angle member attached to the side of the car.

These frame members are secured together by suitable angle clips 22 located at the corners, one flange of each angle clip being attached to one member while the other flange is being attached to the adjacent member. The ends of the flange 12 of the lower Z bars are inwardly offset and respectively connected to the front Z bar 6 and the rear edge angle 15, as indicated respectively at 12°.

The sheet metal panel 5 preferably consists of a plurality of sections 5^a, 5^b and 5^c which are dish shaped; the dished portion of each

section being corrugated in horizontal directions and the corrugations being sufficiently closely spaced to provide proper rigidity, and the sections overlap to shed the rail downwardly. The valleys between the corrugations have terminal flanges which form attaching margins flush with the crests of the corrugations. This feature strengthens the panel and prevents bending at the frame members and reduces the total width of the car in passing thru narrow tunnels or the like. The upper margin of the panel is inwardly offset as indicated at 21 (Figure 2). This inwardly offset portion is attached to the inner side of the depending flange 4 of the top frame member. This feature of construction prevents rain or snow from entering between the frame and panel. The lower margin of the panel is attached to the outer surface of 20 the flange 12 of the lower Z bar and effectively sheds the weather as is obvious.

The lateral margins of the panel are attached respectively to the outer surface of the flange 10 of the front Z bar and to the outer surface of the flange 16 of the rear edge angle of the door. It will be noted that the crests of the corrugations have attaching portions that are flush with the attaching portions of the valleys between the crests.

With reference to Figures 3 and 4 it will be noted that the inner plane of the door panel is normally spaced outwardly from the edge of the floor, whereby it becomes possible to use full head rivets. Where the panel is not thus outwardly offset, it is necessary to countersink the rivets upon the inner side with the result that they soon tear thru.

With reference to Figure 2 it will be observed that a plate 24 which extends throughout the length of the door, connects the panel with the flange 14 of the lower Z bar. This plate strengthens the structure and excludes the weather.

It frequently happens that great difficulty is encountered in opening car doors. In such cases, a grab hook is usually applied to the frontal frame member and a pull is exerted which puts an undue strain upon the frame member. Further, when the door is closed 50 and the rear edge angle on the door strikes the weather proofing flange 19, a severe strain is put upon the rear edge angle. It will be noted that the lateral frame members 6 and 15 are riveted to the panel at their outer flange, so that any strain as heretofore described will tend to produce a turning movement of the said lateral frame members with the result that parts are likely to become badly distorted and damaged. To overcome this, bracing 55 members 23 are attached at one end to the door panel. The other end of each member is in the form of a right angle which is secured to the transverse portion of a lateral frame member. Thus the members 23 at the front 60 edge of the door are attached to the web of

the Z bar as shown in Figure 3, while the rear members 23 are attached to the transverse flange 17 of the rear edge angle 15. Obviously these bracing members tie the lateral frame members to the door panel against turning movement or distortion and thus greatly reinforce the connections between the panel and lateral frame members.

From the foregoing it will be apparent that a very simple structure has been provided 75 which is rigid, strong and durable, and which will not weave or flex when handled or used. It will also be appreciated that the lateral frame members 6 and 15 are rigidly tied to the panel by the bracing members 23 against 80 turning movement. In addition to these advantages, the panel is so connected to the upper and lower frame members so as to shed the rain and weather.

We are aware that many changes may be 85 made, and numerous details of construction may be varied through a wide range without departing from the principles of this invention, and we therefore do not purpose limiting the patent granted hereon, otherwise than 90 necessitated by the prior art.

We claim as our invention:

1. In a metal car door, a panel consisting of a plurality of dish shaped sections, the dished portion of each section being corrugated, the valleys between the corrugations having outwardly offset attaching margins flush with the crests of the corrugations, and the crests of the corrugations having attaching margins flush with said offset 95 margins and a lateral angular frame member having a flange attached to said attaching margins and a web spanning the space defined by the offset margins.

2. In a metal car door, a panel having 105 closely spaced corrugations, the valleys between the corrugations having outwardly offset attaching margins flush with the crests of the corrugations, lateral frame members secured to said attaching margins and crests, upper and lower frame members attached to the upper and lower margins of said panel, and angle clips securing said frame members together.

3. In a car door, a panel having longitudinally extending corrugations, the valleys between the corrugations having outwardly offset attaching margins flush with the crests of the corrugations, said panel having an upper inwardly offset margin, a Z-bar having a depending flange attached exteriorly to said inwardly offset margin, a lower Z-bar having an upstanding flange secured to the inner side of said panel, lateral frame members secured to said outwardly offset margins and to the crests of the corrugations, and means for connecting and bracing said frame members and Z-bars.

4. In a metal car door, a panel having longitudinal corrugations, the valleys be- 130

tween the corrugations having outwardly offset attaching portions flush with the crests of the corrugations, lateral frame members secured to said attaching portions and to the crests of the corrugations, upper and lower frame members attached to said panel, the upper frame member being attached exteriorly of the panel and the lower frame member being attached interiorly of the panel,
5 means for connecting said frame members, and lateral braces connecting said panel and lateral frame members.
10

In testimony whereof, we have hereunto
subscribed our names.
